UNITED STATES PATENT OFFICE.

HECTOR FALLETTA, OF SAN FRANCISCO, CALIFORNIA.

DISINFECTING NOZZLE.

Application filed March 10, 1920. Serial No. 365,067.

To all whom it may concern:

Be it known that I, HECTOR FALLETTA, a subject of Italy, residing in the city and county of San Francisco and State of California, have invented a new and useful Improvement in a Disinfecting Nozzle, of which the following is a specification.

My invention relates to improvements in disinfecting nozzles wherein a liquid germicide is mixed with and projected by water and the objects of my invention are:

First, to provide an improved nozzle wherein a liquid germicide may be mixed with water and projected through said nozzle.

Second, to provide means for mixing a liquid germicide with water projected through a nozzle without lessening the utility of the nozzle when admixture of said germicide is not desired.

Third, to provide an improved nozzle for projecting a liquid germicide with water discharged through said nozzle and adapted to be adjusted to project water and germicide in a spray of the desired character and in a mixture of the desired strength.

I accomplish these and other objects by means of the device disclosed in the drawings forming a part of the present specification wherein like characters of reference are used to designate similar parts throughout said specification and drawings, and in which—

Fig. 1 is a side elevation of a nozzle dis-
closing the tubular member for supplying
a germicide.

Fig. 2 is a longitudinal section of the nozzle shown in Fig. 1.

Fig. 3 is an enlarged sectional view of the dispersing tip.

Fig. 4 is a cross section of the tip taken along the line 4—4 of Fig. 3 in the direction indicated.

Referring to the drawings the numeral 1 is used to designate in general a nozzle. Centrally located within the nozzle is a tubular member 2 provided at its inner end with an interior threaded portion 3 engaging threads 4 formed on one end of a dispersing tip 6, portions of the threads 4 being cut away to form flattened surfaces 7 providing passages 8 between said tip 6 and the inner threaded wall of the tube 2. At the opposite end of the tip 6 is formed a deflecting cone 9 provided with a flattened outer surface 11 having a groove 12 formed

therein, said groove 12 being adapted to engage a screw driver or other suitable tool for adjustment.

The tubular member 2 enters the nozzle 1 through an aperture 14 provided in the side and near the base thereof in such manner as not to interfere with the normal application of the nozzle for use, and is provided with a threaded sleeve 16 adapted to receive one end of a conduit 17 supplying a liquid germicide from a source not shown. A suitable valve 18 is provided in the conduit 17 whereby the supply of germicide may be readily controlled. The tip 6, also serves as an additional means of controlling the supply of germicide as the conical deflecting surface 9 serves to limit the size of the passages 8 and to entirely close said passages 8, when screwed to a position adjacent the end of the tubular member 3.

In use my invention operates as follows. The rush of water through the water chamber 19 of the nozzle 1 causes a fluid germicide, supplied from a suitable container positioned above the level of the nozzle, to be drawn through the passages 8 between the tubular member 2 and the tip 6, and mixed with said water. The mixture is forced through the nozzle aperture 21 by the hydrostatic pressure, and is impinged against the deflecting cone 9 which serves to direct the water and germicide into a spray. The character of the spray may be adjusted by a suitable positioning of the cone 9 or by screwing the tip 6 to approximately the desired position and adjusting with the nozzle tip in the usual manner.

The strength of the resulting mixture of germicide and water may be readily adjusted by increasing or decreasing the supply of germicide, or water, or both as the particular needs may require. Thus a heavy supply of germicide with a light supply of water will give a relatively strong solution which may be readily reduced in strength by increasing the flow of water or by decreasing the supply of germicide.

It is at once obvious that, in this manner, a solution of the germicide of the desired strength may be readily and evenly distributed over the entire surface of an object to be treated without causing a harmful excess to be applied to one portion in order that another portion of the object may be reached. The adjustment of spray makes it readily adaptable to any character of object

or surface without waste of germicide and with a maximum effectiveness.

Having thus described my invention what I claim as new and desire to secure by Letters Patent is—

1. The combination with a nozzle comprising inner and outer casing members forming a mixing chamber within the forward end thereof, of a tubular member centrally mounted within the inner casing and extending outwardly therethrough into the mixing chamber for supplying a liquid germicide thereinto to be mixed with water passing therethrough from the inner casing; a dispersing tip threaded into the forward end of the tubular member, said tip extending outwardly through the outlet of the chamber and nozzle; flattened sides formed upon said tip to permit the passage of germicide from the tubular member into the mixing chamber; and a deflecting cone formed upon the outer end of the tip and positioned outwardly adjacent the outlet of the mixing chamber and nozzle for directing the mixed water and germicide projected therepast into a spray.
2. The combination with a nozzle comprising

inner and outer casing members longitudinally adjustable relative to each other and forming a mixing chamber in the forward end thereof, of a tubular member centrally mounted within the inner casing and extending outwardly through the forward end thereof into the mixing chamber for supplying a liquid germicide thereinto to be mixed within the chamber with water passing therethrough from the inner casing member; a dispersing tip threaded into the forward end of the tubular member, said tip extending outwardly through the outlet of the mixing chamber and nozzle; flattened sides formed upon said tip to permit the passage of germicide from the tubular member past the tip and into the mixing chamber; and a cone formed upon the outer end of the tip and normally positioned adjacent the outer side of the outlet from the chamber and nozzle for directing the mixed germicide and water into a spray adapted to be regulated by adjustment of the outer casing member relative to the cone.

In witness whereof I hereunto set my signature.

HECTOR FALLETTA.
